DESIGN FOR A DRESS ENSEMBLE

John Friedrich Strassner, New York, N. Y.

Application March 17, 1947, Serial No. 137,648

Term of patent 3½ years

(Cl. D3—26)

To all whom it may concern:

Be it known that I, John Friedrich Strassner, a citizen of the United States, residing in New York city, in the county of New York and State of New York, have invented a new, original, and ornamental Design for a Dress Ensemble, of which the following is a specification, reference being had to the accompanying drawing, forming part thereof.

Fig. 1 is a front view of a dress ensemble showing my design.

Fig. 2 is the rear view thereof, on a reduced scale.

Fig. 3 is a fragmentary front view of the dress member of the ensemble shown in Fig. 1, and

Fig. 4 is the rear view thereof, on a reduced scale.

I claim:

The ornamental design for a dress ensemble, substantially as shown.

JOHN FRIEDRICH STRASSNER.
